BENJAMIN CRABTREE, JR., OF PHILADELPHIA, PENNSYLVANIA.

Design No. 3,267, dated December 1, 1868.

DESIGN FOR A CARPET-PATTERN.

The Schedule referred to in these Letters Patent and making part of the same.

To all whom it may concern:

Be it known that I, BENJAMIN CRABTREE, Jr., of the city and county of Philadelphia, and State of Pennsylvania, have invented a new and ornamental Design for a Carpet-Pattern; and I do hereby declare that the accompanying photographic representation fully illustrates my said design.

Having thus described my invention,

What I claim as new, and desire to secure by Letters Patent, is—

The design for carpets, as herein shown and set forth.

To the above, I have signed my name, this 27th day of October, 1868.

BENJAMIN CRABTREE, JR.
